UNITED STATES PATENT OFFICE.

HENRY J. LORANG, OF ST. LOUIS, MISSOURI, ASSIGNOR OF ONE-HALF TO FRANK P. FLORI, OF ST. LOUIS, MISSOURI.

TROUSER SUPPORT.

Application filed December 14, 1925. Serial No. 75,465.

My invention relates to improvements in devices for supporting certain garments from other garments, and more particularly to a trouser support that may be quickly and releasably attached to a shirt, for detachable connection and cooperation with the trouser buttons generally found on the inner side of the waistband of the trouser.

Another of the objects of my invention is 10 to provide a support of the kind described, that will be simple, convenient, light and compact, economical, reliable, and efficient and satisfactory for use wherever found applicable.

15 Many other objects and advantages of the construction herein shown and described will be obvious to those skilled in the art to which this invention appertains, from the disclosures herein given.

20 To this end, my invention consists in the novel construction, arrangement, and combination of parts herein shown and described, and more particularly pointed out in the claims.

25 In the drawings, wherein like reference characters indicate like or corresponding parts throughout the views,

Figure I is a front plan view of my device;

30 Figure II is a side elevation of the same;

Figure III is a rear plan view of the same in opened position, parts being broken away; and

35 Figure IV is a cross-sectional detail taken substantially along the line IV—IV of Figure III.

In the drawings, wherein I have illustrated the preferred embodiment of my invention, 1 indicates the body portion of a 40 shirt of any style, size and shape, and 2 indicates one of the so-called "suspender" buttons, generally found affixed to the inner side of the trouser waist-band, by thread or any other suitable means.

45 The device itself is comprised of two main members, a clamping or gripping member A, and a disk B. The latter is preferably circular and has an arcuate cross-section at its periphery. This disk may be made of 50 any material suitable for the purpose, as for example aluminum, fibre, celluloid, bakelite, etc., all of these materials being non-corrosive under ordinary conditions of wear.

The member A, of a suitable material such 55 as aluminum, is preferably made of two sec-

tions, 3 and 4, respectively, there being a spring 6 arranged at the hinged end 5 of these two sections, whereby the latter will be urged to open position, as shown in Figure III. The parts 3 and 4 are also made 60 arcuate at their peripheries, so as to form an annulus when closed, the degree of curvature of these arcuate cross-sections being approximately that of the disk at its periphery. In this way, the material of the shirt will 65 be clamped or gripped between the disk and clamping member along the peripheries of said members, when the clamping member is closed.

The front side of the section 4 is formed 70 with a forwardly extending or lateral enlargement forming a pocket or socket 7, this socket being adapted to receive the suspender button usually found on the inner side of the waist-band of the trouser, as shown more 75 clearly in Figure I, and to better accomplish its purpose, the socket is provided with a slot or opening 8, extending downwardly, vertically from the top of the socket enlargement as shown. With this construction, 80 the section 4 may be passed upwardly of the button 2 to permit the button to lie within the socket, said slot passing the thread by which the button is secured to the trouser.

In order to releasably hold the clamping 85 member in gripping engagement, I have provided a latch as shown. This latch may comprise a short length of spring brass or the like, as at 9, the same being received within a channel or depression 10 extending 90 radially outwardly of the main arcuate periphery of the section 4. Prongs 11 may be formed for anchoring one end of the spring latch 8 within the channel 10.

The outwardly projecting end of the latch 95 is formed with a series of teeth or notches 12 therein, adapted to cooperate with an inwardly extending notch or tooth 13 provided on the channeled portion 14 of the section 3, similar to the channel 10 formed on the section 4, so that when the sections 3 and 4 are moved to their closed position, the notch 13 will engage with one of the series of notches 12, seating therein to keep the sections in latched gripping position.

In order to provide for the ready and simple release of the latch, I have arranged a dowel pin 15 having its inner end bearing against the spring latch and extending radially and projecting a slight distance be-

yond the section 4. When the dowel is pressed inwardly, it will move the latch from engagement with the notch 13, thereby permitting the spring 6 to spread the sections to their expanded position, as shown in Figure III.

The material of the sections 3 and 4, adjacent their hinged ends is suitably enlarged, as at 16, so that the hinge and spring there-
10 at will not come in contact with the shirt and hence can not soil the same.

In the operation of the device, the disk B is first placed underneath the material of the shirt, and held so, and then the annular
15 clamping member A is clamped about the disk, holding the material of the shirt tightly gripped between the opposed peripheries of the disk and clamping annulus, the disk being sufficiently smaller in circumference
20 than the inner surface of the periphery of the clamping member so that the material of the shirt may lie therein.

The lowermost section 4 is placed adjacent the button 2 of the trouser and passed upwardly so as to guide the latter into the socket 7, the slot in said socket permitting this movement.

Thus the shirt and trousers will be held in proper relationship, and will prevent excess movement of these garments in relatively opposite directions.

It is obvious that in case the clamping member is placed at the side seam of the shirt, a greater clearance between the clamping member and disk should be provided than at other portions, and for this purpose I have enlarged the sections 3 and 4 intermediate their ends, or at their vertical axis, as at 17 and 18. It will also be noticed that the bounding edge of the sections 3 and 4 at their inner side are rounded outwardly at 19, so that there will be no sharp edges or corners coming in contact with the shirt, and hence will avoid tearing of the same.

The disk B may serve an added purpose in that advertising matter as indicated at 20, may be placed thereon.

Having thus described my invention, it is obvious that various immaterial modifications may be made in the same without departing from the spirit of my invention; hence I do not wish to be understood as limiting myself to the exact form, construction,

arrangement and combination of parts herein shown and described, or uses mentioned except as limited by the claims.

What I claim as new and desire to secure by Letters Patent is:—

1. A trouser support comprising a disk, a member adapted to coact with the latter to grip the material of a shirt against both faces of the disk about the periphery of said disk, manually releasable latch means for locking said member in said gripping position, and means on said member for receiving and engaging the trouser button.

2. A trouser support comprising a disk, a two-part annular member adapted to encircle the same and adapted to be detachably secured to said trouser, said annular member being enlarged at its top and bottom to provide greater clearance at said points than at the remainder of the periphery, so as to take care of the seam of a shirt at these points.

3. A trouser support comprising a disk, a member having a periphery adapted to encircle the same and adapted to grip the material of a shirt therebetween, means for releasably locking the member about said disk, and an enlarged trouser-button receiving socket on said member radially inwardly of its disk-encircling periphery, said socket having a vertical slot through the wall thereof.

4. A trouser support comprising a disk, an expansible member adapted to fit about the periphery of the same to clamp the material of a shirt therebetween, a manually operable latch for releasably holding the member in contracted position, and a slotted trouser-button receiving socket on said member, whereby the thread with which said button is fastened may pass through said slot.

5. A trouser support comprising a disk, a two-part member adapted to encircle the same and grip the material of a shirt therebetween, a latch for locking said member in contracted position, a spring pressing said parts apart to release said grip, and an enlarged trouser-button receiving socket on one of said parts, each of said parts being enlarged intermediate its ends, to receive the increased thickness of the shirt at the side seam of the latter.

HENRY J. LORANG.
